UNITED STATES PATENT OFFICE.

EMMETT V. POSTON, OF SPRINGFIELD, ILLINOIS.

MACHINE FOR VENEERING BRICK.

Application filed June 21, 1927. Serial No. 200,343.

My invention relates to a class of machines adapted to be used for veneering and texturing brick units and brick columns from which the brick units may be made, 5 preferably while the body of brick is yet in plastic form, an object being, in my device, particularly to provide a successful means of projecting granular veneer materials forcefully into the plastic exposed faces of the 10 brick column or brick unit so as to substantially embed and impact the veneer materials therein.

An object of my invention is to provide a machine by which I may be able to achieve 15 the process of veneering and texturing brick for which I have filed an application for patent bearing Serial Number 200,347 and filed June 21, 1927.

A particular object of my invention is to 20 provide a machine which will take advantage of the force of gravity to successfully project granular veneer materials into the plastic exposed faces of brick bodies, either in column form or in brick units while in 25 plastic condition, and further to provide in connection with a machine for projecting veneer materials for veneering and texturing brick, a means of mechanically augmenting the gravity movement of the veneer materials by rotatably blasting the same just 30 before they are projected into the plastic brick faces.

A further object of my invention is to provide in connection with a mechanical veneering machine, a means of moistening the 35 granular veneer materials.

I attain the objects of my invention in the device described in the following specifications, recited in the claims and illustrated in 40 the accompanying drawings, in which like reference numerals indicate like parts in the several figures.

Referring to the drawings:

Figure 1 is a front elevation of the machine of my invention.

Figure 2 is a side elevation of the same.

Fig. 3 is a section, 3—3, Fig. 2, of a portion of the hopper and distributing tubes in the machine of my invention.

Fig. 4 is a partial section in detail disclosing the method of releasing the granular particles from the hopper through manually controlled gates.

Fig. 5 is a perspective view of a jet adapted to be attached to the lower ends of the tubes for carrying the granular particles.

Fig. 6 is a vertical section of a detachable jet adapted to be used for augmenting the gravity movement of the veneer particles through the tubes carrying the granular materials from the hopper to the brick body.

Referring in detail to the structure of my device and the means of operating the same, I employ a hopper 1 to hold the supply of veneer materials 2 and have connected to this hopper a suitable number of gravity distributing units 3, 4, 5 and 6, which are adapted to be used for conducting by gravity, the veneer materials down to the moving plastic brick column 14 from suitable heights to produce a gravity force by falling 70 sufficient to substantially embed the falling veneer particles into the plastic exposed faces of the moving column.

It will be evident that the force with 75 which these veneer particles are projected into the plastic brick face may be varied by the variation of the height from which the veneer particles fall through the tubes to strike the plastic brick.

When the force of gravity alone is sufficient, the jet shown in Fig. 3, or a jet of similar purpose, would be sufficient when attached to the lower end of tubes 3, 4, 5 and 6, but when it may be inconvenient or impractical to arrange for the veneer particles to descend from a sufficient height to develop suitable projecting force for the veneer particles, then a jet such as shown in Fig. 5 may be attached to the lower ends of these 80 tubes in order to augment the force by which the particles are projected into the plastic column or brick. In fact, when this jet is used it is possible to obtain suitable projecting force therewith on some occasions sufficient to obviate the need for very much force 85 of gravity.

The veneering materials thus embedded are not again touched by mechanical contact after passing out of the die from which they 100 are formed, but are thus left embedded substantially into the normally exposed faces of the clay column or brick unit and left to present a beautiful, rough, natural texture.

It will be seen that in order to control the 105 flow of veneer particles I provide a hand controlled shaft 7 operatively regulating a plurality of gates 8 which are adapted to control the release of veneer particles from the hopper 1.

A scraper or cleaner 9 is controlled by hand controlled shaft 10 and is adapted to 110

form contact with a rotating drum within the base of hopper 1 for moving the veneer particles to the point of release from the hopper.

5 The drum 23 within the hopper 1 is rotated by a source of power connected with the belt 11.

Conveyor 12 supports and carries the plastic clay column 14 from the die 13.

10 During the process of veneering the workmen commonly experience discomfitures and inconveniences about the point of operation unless there is a hood 15 provided for confining the dust and steam.

15 Referring to Fig. 5, it will be noted that steam pipe or water pipe 16 attaches to jet 17 at a point that will moisten the projected veneer particles as they leave the jet, while in Fig. 6, steam pipe 18 is shown operatively attached to jet 19 for the same purpose.

It will be seen that jet 19 has provided therein a propeller member 20 adapted to be rotated with shaft 21 by a source of power connected with belt pulley 22 for the purpose of boosting and forcefully projecting by a mechanical blast, the moving veneer particles as they leave the tubes.

It will be noted that in the drawings a method of artificially coloring the plastic column or unit brick is not shown, but is to be regarded as optional in connection with my machine, and could be accomplished in a variety of ways, such as for instance by spraying and the like while the column, after veneering, is yet plastic before firing.

30 It will be seen in Fig. 3, and in Fig. 1, that gates 8 are manually controlled by rotating shaft 7, thus providing a convenient means of regulating the release of granular veneer particles from the hopper 1. The 40 position of gates 8 is shown in detail in Fig. 4.

Shafts 10 and 10' are adapted to carry the manually controlled mechanism for 45 regulating the scraper or cleaner for keeping the grooves in rotating drum 23 from clogging under normal operation in order to avoid congestion.

To the skilled brick manufacturer, it will 50 be evident that the force with which the veneer particles may be driven at right angles into the exposed faces of the plastic brick by my machine, will in the gravity fall, depend on the height from which these 55 particles fall, while further variation may be provided in the speed with which propeller 20 in jet 19 may be rotated when it is desired to use the same.

Having thus described the machine of my 60 invention, what I claim is:

1. A machine for texturing brick com-

prising a die for the formation of a plastic brick body, a conveyor for the support and movement of the plastic body, a hopper for the supply of granular texturing materials, 65 a plurality of relatively high gravity conducting tubes adapted to conduct by gravity, said texturing materials from said hopper at right angles to said plastic body; said tubes terminating at the lower ends in a jet registering with the exposed faces of the brick body; said jets each provided with a fluid nozzle for moistening said materials, whereby when controllably released from the hopper, said granular texturing materials will fall from relatively great heights, 70 become moistened, and by the force of the fall, become substantially embedded into the exposed plastic brick faces for forming a 75 veneer therefor.

2. In a veneering machine of the character described, having a die and a conveyor for the formation and movement of a plastic brick body, a hopper and a plurality of gravity conducting tubes; said hopper normally positioned at a relatively great height above the plastic brick body for the support of granular veneering materials, and said tubes adapted to accommodate by force of gravity, the passage of said veneer materials from the hopper at right angles to the exposed faces of the plastic brick body, said tubes provided at their lower terminals with jets adapted to controllably release said gravity accelerated veneer materials thereby projected by the force of their descent and substantially embedded 90 into the plastic faces of the brick body.

3. In a machine of the character described, having a die for the formation of a plastic brick body, a conveyor for the controllable movement thereof, an elevated hopper for containing granular veneering materials, and a plurality of upright tubes adapted to conduct the veneer materials from the hopper at right angles to the brick body, a jet detachably connected to the lower terminals of the tubes and registering with the exposed faces of the brick body; 100 said jet provided with an enclosed rotatable propeller adapted to be operatively connected with driving means for the mechanical acceleration of the gravity movement of said veneer materials through the tubes; 105 whereby said materials may be conducted to and substantially projected and embedded into the plastic faces of the plastic brick body.

In witness whereof, I have hereunto set 110 my signature this 20th day of June, A. D., 115 1927.

EMMETT V. POSTON.
